UNITED STATES PATENT OFFICE.

FRANK Z. HUSAR, OF CHICAGO, ILLINOIS.

ABDOMINAL SUPPORT.

1,399,386.

Specification of Letters Patent.

Patented Dec. 6, 1921.

Application filed November 20, 1917. Serial No. 202,892.

To all whom it may concern:

Be it known that I, FRANK Z. HUSAR, a citizen of the United States, and a resident of the city of Chicago, county of Cook, and State of Illinois, have invented certain new and useful Improvements in Abdominal Supports, of which the following is a specification.

My invention relates to improvements in abdominal supports and has for its object the production of a device of this character, which will afford an effective support for the abdomen and which will be comfortable in use.

15 A further object is the production of a device as mentioned, which will be of durable and economical construction and which may be applied or detached with ease and expedition.

20 Other objects will appear hereinafter.

The invention consists in the combinations and arrangements of parts hereinafter described and claimed.

25 The invention will be best understood by reference to the accompanying drawings forming a part of this specification, and in which,

Figure 1 is a top plan view of an abdominal support embodying the invention,

30 Fig. 2, a perspective view of the construction shown in Fig. 1, showing the relative position assumed by the parts when the device is in use,

Fig. 3, a rear elevation of one of the rear pads of the device, showing the connection thereof with the rearward end of one of the resilient attaching members of the device,

35 Fig. 4, a section taken on line 4—4 of Fig. 3,

40 Fig. 5, a perspective view of another form of the device,

Fig. 6, a plan view showing the relative position assumed by the parts of the construction illustrated in Fig. 5, when worn, and

45 Fig. 7, an enlarged section taken on line 7—7 of Fig. 6.

One form of the construction as illustrated in Figs. 1 to 4, inclusive, comprises a pad 10 preferably of hard rubber which is adapted for engagement with the abdomen of the user, said pad being of slight concave form to adapt the same for snug engagement with the body of the wearer. Said pad is carried by an elongated plate or bar 11, which extends across the front side there-

of, the connection between said bar and pad being such as to permit of free pivotal movement of the said pad about a horizontal axis passing through the points of connection 60 between said pad and bar. The connection between said bar and pad comprises screws 12 which are threaded into spherical enlargements 13, which coöperate with socket-forming plates 14 secured by screws 15 to 65 the outer side of pad 10, said plates having centrally positioned circular openings, as seen, to permit of the partial passage of enlargements 13 therethrough.

The pad is held in position upon the body 70 of the wearer by means of resilient attaching arms 16, which are in the form of blade springs, said members being of a length adapting the same to extend around the sides and snugly embrace the body of the 75 wearer. The front ends of attaching members 16 are pivotally connected with the ends of plate 11 by means of hinges 17. The ends of plate 11 are extended beyond the axes of hinges 17 in order to form stops 80 adapted to limit inward swinging of the members 16. Said members 16 may be covered with a leather casing or housing, as seen, if desired.

Provided at the rearward ends of member 16 are smaller pads 19, which are also so connected with said members as to permit of universal pivotal movement of the same. The connection of said pads with the members 16 is practically the same as the 85 connection of pad 10 with plate 11, comprising a screw 20 provided at its inner end with a spherical enlargement 21 which co-operates with a plate 22 provided upon the pad. Said plate is provided with a circular 90 opening of a diameter slightly less than that of the enlargement, as clearly seen in Fig. 4, with the result that the pad will be permanently fastened, but at the same time will be permitted free pivotal movement. The rearward ends of attaching members 16 are loosely connected by means of a flexible strap 23, having key-hole slots 24 which are adapted to engage with the outer circumferentially grooved ends of screws 20, as 100 clearly seen in Figs. 1 and 4.

By the construction set forth, wherein the pads are arranged so as to permit of free vertical and universal pivotal movement thereof, it is of course apparent that when 110 the device is in use, said pads will readily conform to the curvature or disposition of

the surfaces of the body engaged thereby so that, in the movement of the body, said pads will move therewith and thus lend ease and comfort to the wearer. By providing ball 5 and socket connections between the bar 11 and the pad, in the event of springing of said bar through pressure of the resilient attaching arms 16 connected therewith, there will be no binding such as would otherwise result 10 were hinge joints used in connecting said bar and pad. The hinged connection of the resilient attaching members with the plate 11 permits of ready application of the device, said resilient attaching members being 15 rocked outwardly during application of the device and finally inwardly into snug engagement with the body of the wearer after the pad 10 has been properly positioned against the body of the wearer. The bar 11 is formed with elongated slots at the points 20 of engagement therewith of the screws 12, which permits of relative shifting of the pad 10 to further adapt the device to the precise conditions encountered in individual cases.

25 In the form shown in Figs. 5, 6 and 7, the pad 10 is connected directly with the bar 11 by means of screws 25, said bar being however slotted in the same manner as the bar 11 of the form first described to allow for the desired shifting of the pad relative to said bar. In this form, however, the ends of the bar 11 are secured to the resilient attaching members 16 by means of screws 26, which pass through elongated slots provided in said bar in order 35 to afford lateral adjustment of said attaching members. The rearward ends of attaching members 16 are loosely connected by a strap 23 which is adapted for engagement with the circumferentially grooved heads of 40 screws 27 threaded into the rearward ends

of members 16. This form of the device is used in the same manner as above described, the first described form being adapted however to afford greater ease and comfort to the wearer because of the adjustability of 45 the pad 10 and the employment of additional pivotally adjustable pads at the rearward ends of spring 16.

While I have illustrated and described the preferred forms of construction for carrying my invention into effect, these are capable of variation and modification without departing from the spirit of the invention. I, therefore, do not wish to be limited to the precise details of construction set forth, but 55 desire to avail myself of such variations and modifications as come within the scope of the appended claim.

Having described my invention what I claim as new and desire to secure by Letters 60 Patent is:

An abdominal support comprising a pad; an elongated plate extending horizontally across the front side of said pad; ball and socket connections loosely connecting said 65 pad and plate at a plurality of points so as to permit swinging movement of said pad about only a horizontal axis passing through said ball and socket connections; and attaching means connected with the ends 70 of said plate adapted to embrace the body of the wearer, substantially as described.

In witness whereof I have signed my name to this specification in the presence of 75 two subscribing witnesses.

FRANK Z. HUSAR.
